UNITED STATES PATENT OFFICE.

MICHAEL W. LANE, OF LADOGA, INDIANA, ASSIGNOR OF ONE-THIRD TO
GEORGE ROGERS, OF SAME PLACE.

CAR-COUPING.

SPECIFICATION forming part of Letters Patent No. 253,723, dated February 14, 1882.
Application filed January 16, 1882. (No model.)

To all whom it may concern:

Be it known that I, MICHAEL W. LANE, a citizen of the United States, and a resident of Ladoga, Montgomery county, in the State of Indiana, have invented certain new and useful Improvements in Car-Couplings, of which the following is a specification.

My invention relates to that class of car-couplings intended to connect automatically on the bringing of the cars together; and my invention consists in constructing the parts, as fully described hereinafter, so as to insure the automatic coupling, whatever may be the height of the opposite cars, retain the cars together so long as they remain on the track, and automatically disconnect them should one or more cars be overturned.

My invention further consists of certain improved details of construction, fully described hereinafter.

In the drawings, Figure 1 is a perspective view, showing the end of a box-car with my improved coupling-bar. Fig. 2 is a longitudinal section, showing the draw-bars on opposing cars of different heights. Fig. 3 is a perspective end view of one of the draw-bars. The constructions shown in Fig. 1 and in the remaining figures differ slightly as to details.

Each draw-head A A' has the usual chamber or recess, x, and is provided at the top and front, on opposite sides, with guides a a', slotted to receive the trunnions of a rock-bar, b, from which depends the pin B, the latter having a terminal finger, i, which extends through the bar b, and is secured by a nut, i', so that the pin may be readily removed if bent or worn. The draw-head has slots y y', which permit the pin to swing back, but limit its forward motion after it reaches a vertical position.

The rock-bar b turns in the ends of a yoke, d, which is pivoted to the end of an arm, f, secured to a rock-shaft, g, shown as turning in bearings on the front beam of the car; but when the draw-head is connected to swing under the platform the shaft g may turn in bearings on the draw-head, so as to move with the latter.

The shaft g is provided with a handle, h, at

the side of the car, or in such other position 50 that the shaft may be turned thereby without any risk to the brakeman, who need not pass between the car-bumpers. By turning the shaft the brakeman is thus able to raise the pin from the position shown in Fig. 2 to that 55 shown in Fig. 1. As the brakeman may occupy a position upon the top of a box-car at times when it is necessary to make up or break trains, I connect the shaft g to a lever, h', upon the top of the car, or in a position where it may 60 be readily reached by the brakeman while upon the top. The object in thus raising the pin is to release the link D to disconnect the cars. When cars provided with the two draw-heads are brought together the link D, held in 65 one head, will strike the pin B of the other, and said pin will swing back, as shown in dotted lines at the left, Fig. 2, until the link is fully within the head, when the pin will swing back into the link and secure the latter. It 70 will be apparent that trains of any length may thus be coupled or made up without any further labor on the part of the brakeman than is necessary to insert the links, if the same should not already be in place, and that any 75 car may be uncoupled from its neighbor by simply depressing the arm h or h'.

So long as the cars remain on the track the pins hold the links in place; but should a car be overturned the pins will swing inward, releasing the links, and thus prevent one car from dragging another with it.

Where all the cars are of the same height the devices above described answer all purposes; but it often happens, especially in 85 freight-trains, to which my coupling is particularly adapted, that one car is higher than the next, in which case the link would pass over or under the adjacent draw-head. To avoid this difficulty I combine with each draw-head a link-elevating rod, e, that may be raised or lowered to alter the angle of the link held by the draw-head. This rod may be raised or lowered by different devices. As shown, it is attached to an arm, m, extending to a shaft, n, 90 turning in bearings suitably arranged on the draw-head, and an arm, p, on the shaft n, is connected or jointed to an arm, s, on a shaft,

t, turning in bearings on the buffer-beam, and provided with a handle, *q*, whereby the shaft may be turned.

The mouth of the draw-head has a slot, *u*, in which the rod *e* may lie to prevent it from being struck by the entering link, and the sides of the head have slots *w* to permit the movement of the rod. By depressing the handle *q'* without going between the ears the rod *e* may be raised so as to lift the link to the proper angle to enter the opposing head, as shown in Fig. 2.

The shaft *n* might be extended to the side of the ear and provided with the handle *q*; but by using two shafts, *n* *t*, and linking them together, the swinging of the draw-head independently of the shaft *t* and its handle is permitted.

I claim—

1. The combination of the slotted head, its guides, rock-bar and pin, and the yoke *d*, carrying the rock-bar and jointed to an arm upon a shaft, *g*, substantially as set forth.

2. The combination of the slotted draw-head, rod *e*, shaft *n*, having an arm connected to said rod, and shaft *t*, provided with a handle and connected to said shaft *n*, substantially as set forth.

In testimony whereof I have signed my name to this specification in the presence of two subscribing witnesses.

MICHAEL W. LANE.
